UNITED STATES PATENT OFFICE.

JOHN CURTIS PATTERSON, OF PHILADELPHIA, PENNSYLVANIA.

ART OF PLACER-MINING.

1,325,263.

Specification of Letters Patent. Patented Dec. 16, 1919.

Application filed February 26, 1917. Serial No. 150,894.

To all whom it may concern:

Be it known that I, JOHN CURTIS PATTERSON, of Philadelphia, in the county of Philadelphia and State of Pennsylvania, have 5 invented certain new and useful Improvements in the Art of Placer-Mining, whereof the following is a specification, reference being had to the accompanying drawings.

In order that the nature of my invention 10 may be more readily understood, I have thought it best to preface the description with a general statement in regard to the method usually employed heretofore for the same general purpose, taking as a typical instance both of the old art and of the 15 employment of my invention, a case where the work is to be conducted upon the bed of a stream of running water, the illustrations shown in the drawings being mainly dia- 20 grammatical.

In Figure I, I have illustrated, conventionally, in transverse section, a bed of a stream in connection with devices employed in the method heretofore practised.

25 Fig. II, is a plan view illustrative of said old devices and method, on a reduced scale.

Fig. III, is a plan view of a stream illustrative of the devices and method employed in practising my invention.

30 Fig. IV, is a transverse section of the stream illustrative of my method, the scale of this figure being enlarged and substantially similar to that of the scale of Fig. I.

Referring now to Figs. I, and II, 1, represents the rocky underlying surface of a 35 stream bed, 2, the gravel or other relatively non-coherent material constituting the removable bed of the stream, and carrying the metallic values which are to be separated 40 from the gangue. The dotted lines at 3, indicate the normal water level of the stream.

Heretofore the method of conducting placer mining upon streams of this character was by the use of structures known as 45 wing dams, of which a typical instance is illustrated in Figs. I, and II.

A longitudinal dike of crib work, indicated comprehensively at 4, and built up ordinarily of timbers 5, and 6, placed in alternate pairs and ballasted by pieces of rock 7, was so constructed along the center of the stream bed, following substantially the general course of the stream so as to divide the area as nearly as possible into two equal 55 channels, the direction of flow being indicated by the arrows in Fig. II. At the up-

stream extremity, this central dike of crib work was connected to one of the shores by an inclined crib work 10, (see Fig. II), similar in general character to the crib work of 60 the dike, 4, and constituting the deflecting part of the wing dam. In this manner the water was diverted from that portion of the channel which lay between the longitudinal dike and the adjacent bank at the side to 65 which the wing dam 10, extended, the length of the denuded portion of the bed being of course determined by the longitudinal extent of the dike 4. As a result of this method of procedure, the water of the 70 stream, whose normal level is indicated in Fig. I, by the dotted line 3, was crowded into the remaining channel shown at the left hand side of Fig. I, or the side nearest the observer in Fig. II, and by reason of the 75 diminution of area of cross-section, rose to a level which may be taken as that indicated at 11. The gravel, etc., of the stream bed at the dammed off side of the dike 4, was then removed in any of the ways characteristic of 80 placer mining, and after this the wing dam, represented at 10, was torn down, or disconnected from its original location, and was re-built or reconnected to the opposite bank of the stream, so as to repeat upon the other 85 side of the dike 4, the procedure above described. As thus conducted, the method was open to serious disadvantages among which may be noted the following:

Owing to the structure of the crib work 90 employed, not only was a relatively large portion of the value-bearing bed directly covered by the dike itself, but, in order to insure stability of the dike, the excavation of the uncovered portions of the bed was 95 greatly restricted. Thus, in Fig. II, I have indicated by the dotted lines 15, and 16, respectively, the angle of slope on each side of the dike 4, which was characteristic of the necessary amount of residual material, said 100 material being thus practically lost for the purposes of the mining operation. Speaking roughly, it may be said that the maximum excavation obtainable was represented by that included between a line representing 105 the angle of repose of the material leading from one side of the bottom of the dike to the rocky bed of the stream, the other limit being the bank of the creek at that side.

The crib work dike was necessarily wide 110 in cross-section and required an extended foundation, by reason of the fact that practi-

cally only one such dike could be employed in any given portion of the stream, and consequently the water pressure due to the increased level was relatively high.

5 By the method which I have invented, these objections may be substantially obviated and other advantages may be derived, under similar conditions.

10 Referring now to Figs. III, and IV, 21, represents the rocky bottom of the creek, 22, the removable value-bearing material of the bed, and the dotted line at 23, the normal water level of the stream.

15 At or near the center of the stream, I erect an elongated open trestle work, whose vertical members are indicated at 24, and 25, being preferably timbers pointed at their lower ends and forced by pile drivers into the rocky bottom a sufficient distance to be 20 stable. These uprights are connected at intervals by cross pieces 26, near their upper extremities. On the upper ends of the series of uprights 24, and 25, angle irons 27, or other members adapted to serve as rails, are 25 laid longitudinally with the stream to form a track corresponding in length to the desired length of the dam. Upon the tracks thus formed, a car or platform 30, provided with rollers 31, is supported, said car carrying pile drivers, comprehensively indicated at 34, and 35, respectively. Since the details of such mechanism is well understood, it is not deemed necessary to give more than a conventional representation thereof.

35 The stream is then divided longitudinally into a plurality of channels, preferably three in number, as illustrated in Figs. III, and IV, by means of sheet-piling, formed of steel, extending down through the value 40 bearing loose material, the sheets having interlocking edges which may be made substantially water-tight and being of such rigidity that their lower extremities can be driven firmly into the rocky bed 21, of the stream. As these sheets are successively seated in place they may be stayed at the upper extremities by cross-braces 36, and 37, abutting against the uprights 24, and 25. This adjunctive device, however, may not 45 be necessary in all cases. At the upstream extremity the central channel thus formed between the walls of sheet piling 38, and 39, is closed by a small crib work 40, (see Fig. III), having a double inclined upper end, or 50 by any other suitable device adapted to exclude water from the central channel and divert it to the side channels.

55 Under these circumstances, the conditions illustrated in Figs. III, and IV, will exist, the water level being raised in the respective side channels to a degree illustrated at 41, and 42, so that the external pressure against the longitudinal walls is relatively much less than that which was characteristic 60 of the method shown in Figs. I, and II.

The value-bearing material in the central channel is then excavated, the removal being complete. After this the crib or head of the wing dam 40, is removed. The water is then allowed to reenter the central channel, said wing dam being reconstructed at the up-stream end of one or the other of the side channels previously formed.

70 Under these circumstances, the water will be diverted from that side channel and the excavation of the bed thereof can proceed to the utmost extent required. When this is completed the wing dam crib is removed to the upstream end of the remaining channel and the water is diverted therefrom so that 75 the bed of said channel can be excavated.

80 The braces shown at 36, and 37, may be so constructed and attached as to constitute either compression members or extension members for the support of the sheet-piling, 85 but obviously if the pressure due to the divergence of the water from either of the side channels be so high as to endanger the structure, props or other adjuncts may be employed to support the wall.

90 It will thus be seen that by the employment of my invention, the amount of value-bearing material which is directly covered by any portion of the structure is reduced to a minimum, since even though a crib be 95 employed for the transverse wing dam member, the cross-sectional area thereof is relatively very small. It is obvious however, that even this covered area may be reduced by the employment of sheet-piling or other 100 devices to constitute the angular upstream extremity of the wing dam.

105 I am aware that the use of sheet piling with interlocking edges, is not new, and the reference thereto in the foregoing specification is simply to indicate a preferred feature employed in carrying out the procedure characteristic of my invention.

Having thus described my invention, I 110 claim:

115 1. The hereinbefore described improvement in the art of placer mining of a stream, which consists in separating the water area of the stream and the value-bearing loose material, for an extended distance, into a plurality of longitudinal channels, thinly divided from one another by means extending down through said loose material; successively closing the up-stream extremities of the channels so formed while permitting 120 the water to flow through an open channel; and successively removing the value-bearing material from each closed channel.

125 2. The hereinbefore described improvement in the art of placer mining of a stream, which consists in separating the water area of the stream and the value-bearing loose material, for an extended distance, into three or more longitudinal channels, thinly divided from one another by means extend- 130

ing through said loose material; proceeding, in permutation, to close the up-stream extremity of a channel, while permitting the water to flow through the others; and successively removing the value-bearing material from each closed channel.

In testimony whereof I have hereunto

signed my name at Philadelphia, Pennsylvania, this twenty-first day of February, 1917.

JOHN CURTIS PATTERSON.
